UNITED STATES PATENT OFFICE.

EDWARD E. KLEINSCHMIDT, OF BROOKLYN, NEW YORK, ASSIGNOR, BY MESNE ASSIGNMENTS, TO MORKRUM-KLEINSCHMIDT CORPORATION, OF CHICAGO, ILLINOIS, A CORPORATION OF DELAWARE.

PRINTING TELEGRAPH.

Application filed December 22, 1920. Serial No. 432,564.

To all whom it may concern:

Be it known that I, EDWARD E. KLEINSCHMIDT, a citizen of the United States, residing in New York, borough of Brooklyn, in the county of Kings and State of New York, have invented certain new and useful Improvements in Printing Telegraphs, of which the following is a specification.

One of the objects of my invention is the provision of mechanism, particularly applicable to the Baudot or like systems, in which the usual distributor is dispensed with, and in which line impulses are timed by a rotating member coacting with mechanical means such as movable members, thus eliminating the usual distributor brushes and doing away with one of the sources of trouble and expense in a system of this character.

My invention also has for one of its objects the provision of a receiving device, in which the printing mechanism is controlled by a rotatable member through mechanical means, and which thus does away at the receiving station with the usual distributor. In the usual Baudot system, the letters or characters are received over the line by means of five group impulses; a sixth impulse is used for the purpose of stopping the distributor at the receiving station to bring the same into synchronism with the distributor at the transmitting station, and still another impulse is used to start the distributor at the receiving station. In accordance with my invention, the rotatable member at the receiving station is stopped intermittently in response to one of the group impulses, usually the last impulse, and is started by a single additional impulse having a characteristic different from that of the immediately preceding impulse. In accordance with my invention, therefore, the same amount of information is sent over the line by means of a less number of impulses, which means that the speed of receiving is thereby increased, or that the same speed may be maintained with greater certainty and accuracy.

Still another object of my invention is the provision of a novel signaling mechanism coacting with the message transmitting mechanism.

Other objects of my invention will appear in the specification and will be particularly pointed out in the claims.

My invention will be best understood by reference to the accompanying drawings in which I have illustrated the preferred embodiment of my invention, and in which Fig. 1 is a side elevation, partially in section, illustrating the preferred form of the transmitting mechanism embodied in my invention and showing the cover plate removed to show the working parts: Fig. 2 illustrates the driving mechanism and the associated parts of the transmitter, as viewed from the opposite side of the plate on which the same is mounted; Fig. 3 is a plan view illustrating particularly the receiving mechanism; Fig. 4 is a side elevation, partially in section and partially broken away, and taken from the opposite side of the device from which Fig. 1 is taken; Fig. 5 is a sectional plan view of parts of the transmitting mechanism; Fig. 6 is a fragmentary perspective view of a part of the transmitting mechanism; Fig. 7 is a sectional elevation of the receiving mechanism taken along line 7-7 of Fig. 3; Fig. 7^a is an end view and Fig. 7^b a perspective view of the structure shown in Fig. 7; Fig. 8 is a detail view illustrating the escapement mechanism of the receiver; Fig. 9 is a detail view illustrating the escapement in a different position from that shown in Fig. 8; Fig. 10 is a perspective view of the notched discs with which the rotating member at the receiver is provided, and the cooperating levers controlling certain contacts; Fig. 11 is an end elevation of Fig. 10; Fig. 12 is a plan view of the grooved drum and feed wheel beneath which the tape passes, and of the associated parts; Fig. 13 is a sectional side elevation of the discs and associated parts by which the signalling mechanism and the transmitting mechanism are interlocked; Fig. 14 is a detail view of the mechanical means for operating the signal bell at the transmitting station, and Fig. 15 is a diagram of the electrical connections.

Like reference characters indicate like parts throughout the drawings.

Referring now to the drawings, and first

to the diagram in Fig. 15, 10 is a contact arm at the transmitting station, indicated, in general, at A, the contact vibrating between two stationary contact points 11 and 12 connected to opposite sides of a battery 13, the middle point of which is grounded, as at 14. The vibrating contact arm 10 is connected to the line conductor 15, which includes at the receiving station, in the form here illustrated, a polarized relay 16, the line being grounded at the receiving station, as at 14^a, the receiving station being indicated, in general, by the character B. In the Baudot system, each letter or character is usually sent by means of a group of five impulses having different polarities to produce the desired combinations. I have illustrated at 17, 18, 19, 20 and 21, the usual selector magnets, as well as the sixth impulse magnet 22, which initiates the printing. These magnets are all included in a local circuit 23, comprising a source of electric energy, such as a battery 24. The respective circuits of the magnets 17, 18, 19, 20, 21 and 22 are controlled by sets of contacts 25, 25^a, 26, 26^a, 27, 27^a, 28, 28^a, 29, 29^a and 30, 30^a, respectively.

Referring now to Figs. 1, 2 and 4, 31 indicates, in general, the frame of the machine comprising a bed plate 32, on which is mounted the operating motor 33, a base plate 34 being secured to the bed plate 32 and carrying the upright plate 34^a, on which most of the parts of the transmitting mechanism have their bearings. The vibrating arm 10, referred to in connection with Fig. 15, is mounted on an elbow lever 35, pivoted at 36 in a bracket 37, mounted on the base plate 34. A spring 39 is connected to the lever 35 and to a stationary part of the device and tends to move the arm 10 against the contact point 12 which, in the specific embodiment of my invention here shown, is the negative contact, contact point 11 being the positive contact. Beneath the lever 35 is disposed a plurality of arms indicated, in general, at 40, (see Figs. 1 and 5) and which are individually represented by the reference characters 40^a, 40^b, 40^c, 40^d, 40^e and 40^f. The horizontal portion of the elbow lever 35 extends across all six of the arms, so that the elevation of any one of the arms will rock the elbow lever 35 and move the contact arm 10 against the contact at the right, as viewed in Fig. 1. A spring 41 is provided for each of the arms 40, one end of the spring being attached to the upper side of the arm, and the other end to a stationary part, so that the spring tends to elevate the arms against the action of the spring 39, and the springs 41 are sufficiently powerful to overcome the springs 39 and move the arms when the latter are unrestrained. To each of the arms 40^a, 40^b, 40^c, 40^d and 40^e are pivoted, when

used in the Baudot system, five upwardly extending plungers 43, the upper ends of which are preferably cylindrical and pass through slots 44 in a plate 45, secured to the upright plate 34^a, the upper ends of the plungers cooperating with a perforated tape, in a well understood manner. An additional guide plate 47 is preferably secured to the underside of the plate 45 and is provided with slots 48, through which the five plungers also pass. The plungers 43 are moved to the right, as viewed in Fig. 1, by springs 49 which bring the plungers into engagement with set screws or other stops, by means of which the positions of the plungers may be adjusted. No plunger is connected to the sixth arm 40^f which is actuated by its spring 41 each time the arm is released, in the manner hereinafter described.

The tape 51 has a message perforated thereon, by means of a separate instrument of any suitable character. The tape passes beneath a roll 52, provided with peripheral grooves 53 (Fig. 12), which register with the upper cylindrical ends of the plungers 43, so that when a perforation in the tape comes above the plunger, the plunger passes through the perforation into the registering groove 53. The perforations 54, Fig. 12, produce the group of five impulses of the Baudot code, and 55 are a series of feed holes which are engaged by teeth 56 on the roll 52. The roll 52 is rotatably mounted on a pintle 57 which passes through an arcuate slot 58 in the plate 34^a and is secured to one arm of a bell-crank 59, pivoted at 60, the other arm of the bell-crank being provided with an operating handle 61, passing through an arcuate slot 62 in the plate 34^a. A guide plate 63 for the tape is mounted on the plate 45 in front of the roll 52, a post 64 preferably being provided to keep the tape in the groove 63^a, formed in the guide plate. A stripping plate 65, secured to the plate 34^a, preferably extends across and above the tape to disengage the latter from the feed wheel.

Levers, indicated, in general, at 66, and individually by the reference characters 66^a, 66^b, 66^c, 66^d, 66^e and 66^f, are pivoted at 67 and engage the free ends of the arms 40^a, 40^b, 40^c, 40^d, 40^e and 40^f, respectively. The opposite ends of the levers 66 are provided with projections 68 which are engaged by cams 69, secured to and angularly displaced with reference to each other on a shaft 70, having its bearings at 70^a in the frame of the machine (see Fig. 5), so that the cams successively engage the ends of the operating levers 66^a, 66^b, 66^c, 66^d, 66^e and 66^f. Each cam arm is preferably extended to the diametrically opposite sides of the shaft, so that each of the arms 66 is twice operated during each revolution of the shaft 70 on which the cams are mounted.

The connections by which the operating cams, just referred to, are actuated by the motor include the shaft 71 of the motor which has its bearings at 71^a in brackets secured to the frame. On this shaft is mounted a worm 72 (see Fig. 4) engaging a worm wheel 73 rotatably mounted on the shaft 70, suitable ball-bearings 74 preferably being interposed between the worm wheel 73 and the shaft. A slip friction, indicated, in general, at 75, is interposed between the worm wheel 73 and the shaft 70, so that the motor may continue to rotate while the transmitting device is inactive. A friction plate 76 engages the face of the worm wheel 73 and is attached to, or integral with, a hub 77 surrounding the shaft 70. A collar 78 is mounted adjacent to the hub 77 and is provided with lugs 79, engaging in corresponding recesses in the hub 77, so that the two parts rotate together. The end of the collar 78 is preferably enlarged, as at 80, and secured to the shaft by a set screw 81, a coiled spring 82 being interposed between the enlarged end 80 of the collar and the friction plate 76, to produce the desired friction between the plate and the gear.

The roll 52 is driven by means of a pinion 85, secured on the shaft 70 acting through gears 86, 87 and 88, (see Figs. 1, 2 and 5), the latter being secured to rotate with the roll 52, it being understood that the gear wheel 88 rotates when the roll 52 is elevated by the handle 61. The elbow lever 59, on which the roll 52 is mounted, is normally held in the position, shown in Figs. 1 and 2, by a spring 89, (see Fig. 2), attached to an arm 90, secured on the rock shaft on which the elbow lever 59 is mounted, an adjustable set screw 91 preferably being attached to the elbow lever and engaging a stop, such as a screw 92 (see Fig. 2). The elbow lever 59, when moved clockwise, as viewed in Fig. 2, is held in position by a friction spring 93, secured on one side of the vertical plate 34.

In the embodiment of the invention here illustrated, the different characteristics of the impulses are produced by varying the polarity of the group impulses, and an additional impulse is provided having a different polarity from that of the fifth or last group impulse. That plunger 43 which is pivoted to the arm 40^a, producing the last of the group impulses, is provided with a pin 94 which engages an arm 95, secured on a shaft 96, (see Fig. 6), when this particular plunger is elevated. The rock shaft 96 is held in one or the other of its positions by a spring finger 97, Fig. 1, the bent end of the spring engaging on one side or the other of a triangular lug 97^a. A downwardly extending arm 99 is also secured to the shaft 96 and is provided at its lower end with a horizontal extension 100, which is

adapted to engage a hook 101, secured to the lower side of the sixth impulse lever 66^a. When, therefore, the last of the group impulses is a positive impulse, the end of the plunger 43 passes upwardly through the 70 tape, the pin 94 engages the arm 95, rocks the shaft 96 and brings extension 100 on the lower end of the arm 99 over the hook 101, so that when the last cam arm 69 engages the corresponding lever 66^a and releases the corresponding arm 40^a, the latter cannot be elevated because of the lock engagement, and the contact 10 is locked against the contact 12, so that a negative impulse is sent, 75 having a polarity diverse from that of the 80 last of the group impulses. When, on the other hand, the last group impulse is a negative impulse, the plunger 43, corresponding to the last group impulse, is not raised, the pin 94 does not engage the arm 95 to 85 rock the shaft, and the extension 100 does not come into engagement with the hook 101, so that when the lever 66^a is rocked by the corresponding cam arm, the corresponding arm 40^a is elevated, contact arm 10 is brought 90 into engagement with contact 11, and a positive impulse is sent over the line. It will be seen, therefore, that the additional sixth impulse always has a polarity the reverse of the last group impulse. A second 95 arm 102 is secured to the shaft 96 and is engaged by a lug 103, on one of the lever arms 66, here shown as the second lever arm 66^b, which, when the lever is elevated, engages the arm 102, rocks the shaft 96 and causes 100 the arm 95 to be depressed, thereby returning the extension 100 to its normal position.

The signaling mechanism comprises a code wheel 104, secured on a shaft 105, having its bearings at 106 in the plate 34^a, and in a bracket secured to the bed plate, respectively. On the end of the shaft 105, opposite to the cam wheel, is secured a gear wheel 107, meshing with a gear 108, formed on a collar 109, secured on a hub 110, surrounding the shaft 105, the hub preferably being integral with a friction disc 111, engaging the gear wheel 73 on the opposite face from the friction disc 76, the parts, associated with the collar 109, engaging a collar 112, secured to the shaft, so that the friction disc 111 is held in engagement with the face of the gear wheel by the same spring 82 which holds the friction disc 76 in engagement with the same gear wheel. It will thus be seen that the transmitting mechanism and the signaling mechanism are both geared to the same motor, and interlocking mechanism is provided, which stops the movement of the transmitting mechanism, when the signaling mechanism is put into operation, and vice versa. A spring arm 113 (see Fig. 2) is provided at its upper end with an operating handle 114, passing through a slot 115 in the plate 34^a. The spring arm 113 is secured at its 130

lower end on a shaft 116, having its bearings at 117 in plates 34^a and 34^b, secured to the base plate. Secured on shaft 116 is another arm 118 (see Fig. 13), to the upper end of 5 which is secured a roller 119 (see Fig. 13) and laterally extending projections 120 and 120^a (see Fig. 5), forming detents, the roller and the detents cooperating with discs 121 and 122, secured on shafts 70 10 and 105, respectively. The disc 121 is provided, on diametrically opposite sides, with notches 121^a which cooperate with roller 119, while disc 122 is provided with a single notch, 122^a within which detent 120 15 is received. Discs 121 and 122, together with the notches and the cooperating roller and detent, are so arranged that, when the roller is received in one of notches 121^a, detent 120 is withdrawn from notch 122^a in disc 122, 20 and detent 120^a is simultaneously brought into the path of movement of an arm 138, secured to a collar 70^b, which is, in turn, secured to shaft 70, thereby arresting the transmitting mechanism. On the other hand, 25 when notch 122^a in disc 122 is presented to detent 120, the detent is drawn into the notch by a spring 118^a, attached to arm 118, which normally maintains the detent in position. When the operator desires to send a 30 signal over the line, he throws the handle 114 to the right, as viewed in Fig. 1. This movement of the handle flexes spring arm 113 and tends to rock shaft 116 clockwise, and as soon as one of the notches 121^a in 35 disc 121 is brought opposite roller 119, and at the same time arm 96^a is out of the way of arm 116^a, the roller will be moved to the right, as viewed in Fig. 13, and the movement of the transmitting mechanism will 40 thereby be stopped. The signaling mechanism, which has hitherto been inactive, because of the friction disc 11, slipping on the gear wheel 73, now begins to operate and code wheel 104 transmits a desired signal 45 over the line. This is done by operating the same contacts that are used during transmission, cam wheel 104 engaging one arm of a bell-crank 123, pivoted at 123^a, which is kept in engagement with the code wheel by a tension spring 124, the opposite arm of bell-crank 123 engaging the end on 50 one of the levers 66, here shown as the sixth impulse lever 66^f. Code wheel 104 is provided with any desired number of teeth 104^a, 55 suitably formed, and a complete revolution of the code wheel produces a desired signal at the receiving station. In actuating the signaling mechanism with the code wheel illustrated, a plurality of impulses forming 60 signals, the precise nature of which it is unnecessary to describe, are sent over the line. When the code wheel cam is started from the position shown in Fig. 1, arm 123 is brought into engagement with the first tooth 65 104^b and a starting or sixth impulse is sent

over the line. It is necessary for the operation of the system that this impulse should have a characteristic different from that of the last group impulse of the transmitting mechanism. It is convenient, however, to 70 arrange the code wheel so that the sixth impulse is of a fixed characteristic, here shown as a positive characteristic. This means that the transmitting mechanism must be stopped only, when the last group 75 impulse is of a different characteristic from that of the starting impulse of the signaling mechanism—in this case a negative impulse. Mechanical interlocking means are, therefore, provided which permit the signal mechanism 80 to start only when the last group impulse is a negative impulse. An arm 96^a is secured to shaft 96, which coacts with an arm 116^a attached to shaft 116, to which spring arm 113 is secured, and the parts are so arranged 85 that when the last group impulse is negative, the arm 96^a engages the arm 116^a, thereby preventing the rotation of the shaft 116, necessary to the starting of the signaling 90 mechanism, and the transmitting mechanism 95 will continue to operate until the last group impulse is negative. In the embodiment here illustrated, three different signals which may be "carriage shift," the letter "J," and "carriage release," are sent by the code wheel. It may be remarked, however, that the successive starting impulses of the code wheel are of different characteristics from those of the immediately preceding group 100 impulses, the same as in the transmitting mechanism, and at the end of a given signal, the cam on the arm 123 drops off from the cam 104^a, on the wheel immediately below the cam on the arm 123, Fig. 1, and sends a negative starting impulse, which starts the receiver. The extended notch in which the cam on the arm 123 is shown positioned in 105 Fig. 1, permits the continued rotation of the code wheel 104, after the cam has dropped into its notch, and this permits the movement of the receiver to be arrested, before the transmitting mechanism begins operation. The signal at the receiving station may be a single stroke of a bell which is 110 likewise produced at the transmitting station by a mechanical arrangement, reference being had particularly to Figs. 5 and 14. The bell is indicated at 125. A bell-crank 126 pivoted at 127 is provided with one arm 126^a, adjacent to the gear wheel 107. The other arm 126^b is normally held against a stop 128 by a spring 129. The free end of the arm 126^b is provided with a hammer 126^c. A lug 107^a is secured on the face of 115 the gear wheel 107 which engages the arm 126^a from below and rocks the bell-crank, and when the lug 107^a is disengaged from the arm 126^a, the bell-crank is returned to its normal position by spring 129 with sufficient force to cause the hammer 126^c to en- 120 125 130

gage the bell and give the operator an audible indication that the signaling member has completed one revolution and that a corresponding signal has been given at the receiving station. The operator will hold the handle 114 in the position at the right, as viewed in Fig. 6, until the desired number of signals have been transmitted and when released, the rock shaft 116, to which the 10 spring arm is secured, is returned to its normal position by a spring 118^a, (see Fig. 13), when the notch 121^a in the disc 121 is brought opposite the detent 120.

Mechanism is preferably provided for 15 stopping the operation of the transmitting mechanism, in case the slack in the tape is taken up to such an extent that the tape is likely to break. The tape, as it is fed to the machine, passes beneath a lateral extension 130, (see Fig. 2), on an arm 131 which is secured to a shaft 132. To the shaft is secured an upwardly extending arm 133, having at its upper end a lateral projection 134, to which is attached the upper end of 20 an over-centering spring 135, the lower end of which is attached to an arm 136, pivoted at its upper end 137, so that, when the lower end of the arm is moved to the right, as viewed in Fig. 2, it comes in the path of 25 movement of the arm 138, secured on the shaft 70 of the transmitting mechanism, to stop the operation thereof. When the arm 131 is raised, by the slack being taken up in the tape, the upper end of the arm 133 30 is moved to the right, which moves the spring 135 past the center of the pivot 137 of the arm 136 and causes the lower end of the arm to snap to the right into the path of movement of the arm 138 on the shaft 70, 35 and thereby stops the operation of the transmitting mechanism. When there is again sufficient slack in the tape, the arm 131 drops and moves the arm 133 out of engagement with the arm 138.

40 In Figs. 3 and 4, a centrifugal arrangement is shown for producing substantially constant rotation of the motor. A fly-wheel 139 is secured on the shaft 71 and is provided at one side with a recess 140, in which 45 is suitably mounted a strap spring 141, to which is secured, beyond the center, weights 142 which preferably pass through openings 142^a in the fly-wheel. Any movement above normal of the fly-wheel causes the weights 50 55 142 to flex the spring 141 to such an extent, as to withdraw a thrust bearing 143, carried by the spring, from engagement with an arm 144, pivoted at 145. The outer end of the arm 144 carries a contact 146 which normally engages a contact 147, the contacts being included in the armature circuit of the motor. When the speed of the motor increases beyond normal, and correspondingly that of the fly-wheel, the contacts are 60 65 opened, introducing resistance in series with

the armature, and thereby reducing the speed of the motor.

In the receiving mechanism which cooperates with the transmitting mechanism, worm 72 on shaft 71 is engaged by a second worm wheel 148, (see Fig. 4), secured on a vertical shaft 149, having its bearings at 150 and 151 in the bed plate and in a plate 152, secured, by means of posts 153, to the bed plate. On shaft 149 is secured a rotating member, indicated in general, at 154, and comprising discs 154^a, 154^b, 154^c, 154^d, 154^e and 154^f. Each disc is provided, on diametrically opposite sides, with notches 155, 70 75 Figs. 11 and 15, and as will be apparent 80 from an inspection of the disc 154^f, shown in Fig. 10, the notches in the successive discs being angularly displaced, with reference to each other.

Rotating member 154 is rotated at a speed 85 very slightly in excess of that of cams 69 at the transmitting station, and is stopped and started twice at each revolution, to keep the same in synchronism with the rotating member at the transmitting station. A magnet 156, (see Fig. 15), is included in the local 90 circuit 23 of the receiving station. One terminal of this magnet is connected to one pole of local battery 24, while the opposite 95 terminal of the magnet is connected to the opposite pole of the battery through armature 16^a of the polarized relay. Magnet 156, therefore, is energized in response to each positive impulse and is not energized when a negative impulse comes over the line. Now, 100 in order that selector magnets 17, 18, 19, 20 and 21 may be energized in response to certain impulses, here shown as the positive impulse, and in order that the magnets may not be energized in response to the impulse of opposite polarity, means are provided 105 whereby the line circuits, including the respective selector magnets, are closed in response to positive line impulses, but prevent the circuits, including the selector magnets, 110 from being closed, in response to negative line impulses. Arms 157 are pivoted at 158 and are formed at their ends with lugs 159 which register with discs 154 and are adapted 115 to be received in notches 155 thereof, and thereby permit the arms to drop, provided they are otherwise free. The arms in their normally raised positions engage the respective contact springs 25, 26, 27, 28, 29 and 30 and hold them out of engagement with their 120 cooperating contact points. The magnet 156 is provided with an armature 160, mounted on an arm 161, pivoted at 162, the free end of arm 161 being provided with a universal 125 bar 163, Fig 7, which is normally disposed opposite lugs 164, formed on the one side of the five arms 157 controlling springs 25 to 29, inclusive, when armature 160 is in its normally retracted position, as shown in 130 Figs. 3 and 15, arm 161 being held against

a stop 165 by a spring 166. Arm 157 controlling spring 30 is not controlled by the universal bar 163 and is permitted to close as will be seen in Figure 7 immediately after 5 the springs 21 to 25 have been set in accordance with the incoming impulses, to operate the sixth pulse magnet 22. It will be seen that a local impulse operates the sixth pulse magnet after each code combination has been 10 set up on magnets 17 to 21. With the parts in the position shown in Fig. 3 and the universal bar 163 directly opposite lugs 164, the lugs engage the universal bar and arms 157 cannot drop into notches 155, under pressure 15 of contact springs 25 to 29. Now, when a positive impulse comes over the line, armature 16^a, Fig. 15, is closed against the front contact, the circuit, including magnet 156, is thereby closed and the magnet energized, 20 thereby attracting armature 160 and withdrawing universal bar 163 from lugs 164, including that lever whose lug 159 will come opposite the notch 155, at the time corresponding to the assumed positive impulse. 25 One arm 157 will thereby drop, closing corresponding contacts 25, 25^a to the corresponding selector magnet. When, however, a negative impulse comes over the line, magnet 156 is not energized, armature 160 re- 30 mains in its retracted position, thus leaving universal bar 163 opposite lugs 164, and when a notch 155 in a cooperating disc 154 comes opposite a lug 159, the corresponding lever 157 cannot drop into the notch, with 35 the consequence that the corresponding contacts remain open and the corresponding selector magnet is not energized. It will be seen, therefore, that the selector mechanism is under the joint control of the line impulses 40 and the rotatable member at the receiving station.

The means for stopping and starting the rotating member of the receiving device during each revolution, and thereby keeping 45 the same in cyclic synchronism with the movement of the rotating member at the transmitter, comprise an escapement, including two diametrically opposite arms 167, Fig. 7, secured to the face of one of the 50 rotating discs 154 and each carrying at its end a detent 168 pivoted at 168^a and cooperating with two arms 169 and 170, pivoted at 171, Fig. 8, and biased to move towards each other by springs 172, connected to extensions 55 173, at the ends of the arms. An arm 174 is secured to member 161 which is actuated by armature 160 and extends between arms 169 and 170. When the armature is retracted, arm 174 will engage arm 170 and move it in one direction, and when the armature is attracted by its magnet, arm 174 will engage arm 169 and move it in the opposite direction. The detent 168 is constructed and arranged to engage the ends of one or the 60 other of arms 169 or 170, and when it so

engages either arm, the detent is tilted about pivot 168^a, so as to be freed from the other arm. In Fig. 8, detent 168 is engaged by the side extension of arm 169, and thereby tilted up, so as to clear the face extension of arm 170, while in Fig. 9, it is engaged by the face extension of arm 170, and thereby tilted down, so as to glide along the side extension of arm 169. The last impulse of the group impulses coming over the line, whether it be 70 positive or negative, causes detent 168 to engage one or the other of arms 169 or 170, depending upon whether this last impulse is positive or negative. Now, when the additional impulse having a polarity the opposite 75 to that of the last group impulse, comes over the line, arm 174 will move the other arm to release the detent, so that the rotating member of the receiving device is always stopped by the last group impulse and is started in 80 response to the additional impulse.

A friction device, indicated, in general, at 175, is provided for the rotating member of the receiving device, and as this friction member is similar to that already described 90 in connection with the transmitting device, the same need not be described in detail.

The operation of the described printing telegraph is as follows: Assume that the operator desires to send the letter "a". In the 95 Baudot code, this letter is formed by two positive impulses, followed by three negative impulses. As the tape passes through the transmitter, perforations, forming the letter "a" transversely of the tape, will be made up of two perforations in the first two spaces, followed by three blanks. When cams 69, therefore, successively engage the ends of the first two levers 66^a, 66^b, the opposite ends of these levers will be elevated, thereby permitting springs 41 to lift successively the first two arms 40^a and 40^b, as the upper ends of plungers 43 pass through the first two perforations of the tape. The movement of arms 40^a and 40^b will successively move contact tongue 10 into engagement with contact point 11, thereby sending two successive positive impulses over the line. The two positive impulses, passing over the line, will bring the armature 16^a of relay 16 into engagement with its contact points at the times when notches 155^a and 155^b of discs 154^a and 154^b are opposite lugs 159 on levers 157, thereby permitting levers 157 to drop into the notches, since magnet 156 has withdrawn universal bar 163 from lugs 164 on the levers 157. The two sets of contacts 25, 25^a, 26, 26^a are, therefore, successively closed, and selector magnets 17 and 18 are successively energized. When the three next operating levers 66^c, 66^d and 66^e are actuated by the three succeeding cam arms 69, the opposite ends are lifted from corresponding arms 40^c, 40^d and 40^e, but the latter are not permitted to rise, since their up-

per ends are in engagement with the tape, the three last spaces corresponding to the group of impulses, being blanks. Contact tongue 10, therefore, remains in engagement with contact point 12, so that, in effect, three negative impulses are sent over the line. During this period of operation of the transmitter, the armature 16^a of polarized relay 16 is moved away from its contact point 10 with the result that as notches 155^c, 155^d and 155^e of discs 154^c, 154^d and 154^e come opposite lugs 159, the latter are not permitted to drop in the notches, since magnet 156 which is controlled by armature 16^a is not energized, universal bar 163 remains opposite lugs 164 of the last three levers 157 and contacts 27, 27^a, 28, 28^a and 29, 29^a remain open, with the result that the three selector magnets 19, 20 and 21 remain deenergized, thereby setting up the desired combination in the printer. Whether the last impulse of the group of five impulses is positive or negative, the movement of armature 160 in one direction or the other, will move one or the other of arms 169 or 170 and thereby stop the movement of the rotating member of the receiver, as heretofore explained. Now, when the additional sixth impulse, which is of opposite polarity to that of the last of the group impulses, comes over the line, armature 160 is moved in the opposite direction, the other arm 169 or 170 is moved in the opposite direction from the preceding arm and detent 168 is released, thereby starting the rotating member of the receiver in synchronism with the rotating member of the transmitter.

In case the operator desires to transmit a signal to another station, he moves operating handle 114 to the right and holds it in this position until one of the notches 121^a in disc 121 comes opposite roller 119 when the latter will engage the notch, thereby freeing disc 122, thus stopping the movement of the transmitting mechanism and starting the movement of the signaling mechanism. The cams 104^a on the code wheel 104 are formed to send through the levers 123, 66^f and 40^f, the contact tongue 10, and contact points 11 and 12 the desired signal to the receiving station. When the code wheel of the signaling mechanism has completed its movement, a signal, such as the ringing of a bell, is given at the receiving station and a corresponding signal, given at the transmitting station through lug 107^a, engaging arm 126^a, as heretofore described. The operator continues to hold handle 114 to the right until the desired number of signals, conveying the desired information, have been given. Since the signaling mechanism is driven by the same motor that drives the transmitting mechanism, it will be apparent that signals are

sent without loss of time, and since they are transmitted through the same mechanism by which the regular transmitter operates, the signals will be given with the same certainty as that of the message sent by the transmitter.

What I claim and desire to secure by Letters Patent of the United States is:

1. The combination with a telegraph printer, of a selector, means for controlling said selector, responsive to line impulses and including a plurality of movable members and a rotatable member cooperating with said movable members and arranged to permit them to move successively, and additional means operating in response to a line impulse of one characteristic to restrain said members and in response to a line impulse of a different characteristic to permit movement of said members, said selector comprising electro-magnetic devices and contacts controlled by said members and, in turn, controlling said electro-magnetic devices. 75

2. A start-stop telegraph system embodying a tape perforator, a transmitting apparatus into which said tape is fed from said tape perforator, comprising means controlled by the perforated combinations in said tape to transmit code combinations of 80

selecting impulses, and means independent 85 of control by the perforated combinations for preceding each code combination of selecting impulses with a receiver start condition; a receiving distributor started into a cycle of operation by said start condition and arrested in operation at the end of a complete cycle, and control means interposed 90 between said perforator and said transmitter controlled by the tension of said tape for arresting the operation of said transmitting apparatus only between the transmission of completed code combinations of selecting impulses and in a position to transmit a continued receiver stop condition in a manner to maintain said receiving distributor at rest 95 until said tape controlled means again initiates operation of said transmitting apparatus; said start condition being always different in character from said stop condition. 100

3. The system as set forth in claim 2 in 105 which said stop condition is the same in character as the last selecting impulse of a code combination of selecting impulses. 110

4. A system of telegraphy comprising 115 transmitting means operating continuously and at a uniform rate to transmit code combinations of electrical selecting conditions each preceded by a receiver start condition differing in character from the last selecting condition entering into the preceding code combination; and a receiver stopped in operation at the end of each code combination and started into operation by said receiver start condition preceding the reception of each code combination. 120

5. The system as set forth in claim 4 in which said transmitting means comprises a continuously operating tape transmitter.

6. In telegraph system comprising apparatus for transmitting code combinations of marking and spacing conditions with a start condition preceding each code combination, said start condition being different in character from the last condition of the preceding code combination; a receiver comprising a plurality of selector members, a rotary member controlling said selector members, a selector magnet, an armature for said selector magnet mechanically controlling said selector members, and a mechanical stop member for said rotary member actuated by said armature to release said rotary member for rotation in response to each start condition.

7. In telegraph system comprising apparatus for transmitting code combinations of marking and spacing conditions with a start condition preceding each code combination; said start condition being different in character from the last condition of the preceding code combination; a receiver comprising a plurality of selector members, a rotary member permitting successive operation of said selector members, a magnet, an armature for said magnet adapted to interfere with the successive movement of said selector members in response to received code combinations, and a mechanical stop for said rotary member actuated by said magnet in response to each start condition.

ing code combination; a receiver comprising a plurality of selector members, a rotary member permitting successive operation of said selector members, a magnet, an armature for said magnet adapted to interfere with the successive movement of said selector members in response to received code combinations, and a mechanical stop for said rotary member actuated by said magnet in response to each start condition. 30

8. The combination as set forth in claim 7 in which said selector members comprise a plurality of switches, together with a set of selector magnets controlled by said switches.

9. Selecting receiving apparatus responsive to code combinations of selecting conditions, and starting into operation at the beginning of each code combination by a start condition differing in character from the last selecting condition of the preceding code combination comprising a rotary member, a magnet responsive to all of said conditions, and a plurality of stops for said rotary member actuated by said magnet. 40
